(57) **CLAIM**

The ornamental design for an irrigation controller, as shown and described.

DESCRIPTION

FIG. 1 is a front, right and bottom perspective view of an irrigation controller, showing our design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the irrigation controller that form no part of the claimed design.
